UNITED STATES PATENT OFFICE.

FRANK. E. WILCOX, OF BATAVIA, NEW YORK.

REACH-SOCKET.

SPECIFICATION forming part of Letters Patent No. 439,827, dated November 4, 1890.

Application filed June 30, 1890. Serial No. 357,291. (No model.)

To all whom it may concern:

Be it known that I, FRANK. E. WILCOX, a citizen of the United States, residing at Batavia, in the county of Genesee and State of New York, have invented certain new and useful Improvements in Reach-Sockets; and I do hereby declare the following to be a full, clear, and exact description of the invention, such as will enable others skilled in the art to which it appertains to make and use the same.

My invention has for its object to simplify and cheapen and at the same time to greatly improve the construction of reach-sockets.

With this end in view I have devised the simple and novel construction of which the following description, in connection with the accompanying drawings, is a specification, numerals being used to denote the several parts.

Figure 1 is a cross-section of the axle of a wagon, showing my novel reach-socket and the reach and clip in elevation; Fig. 2, plan views of the two parts of my novel reach-socket detached, the upper part being inverted; Fig. 3, a cross-section, the line being indicated by *a* in Fig. 1; and Fig. 4 is a longitudinal section of the rear end of a reach-socket in which the rib and groove are omitted.

Heretofore reach-sockets of this class have ordinarily been formed from a single piece of metal, the inner end of which has been split and the two arms of the socket bent outward and drawn to proper shape to inclose the end of the reach. This method of making has been slow and expensive, and, moreover, has required the very best of workmen. My present invention enables me to strike up a reach-socket in two parts from ordinary strips or rods of metal, thereby doing away with skilled labor entirely and enabling all the work to be done with an ordinary power-hammer, and the use for stock of ordinary strips or rods of iron of suitable size.

1 denotes the upper part of the socket, and 2 the lower part. I preferably form the two parts to an outline in side elevation substantially as shown in Fig. 1, although it will of course be apparent that the exact shape of either of the parts is not of the essence of my invention.

3 denotes the axle, and 4 the clip, by which

the reach-socket is secured to the axle, the two ends of the clip passing through corresponding holes 5 in the two parts of the reach-socket and being secured on the under side by nuts 6 or in any ordinary simple manner. It will be noticed that the under side of the axle is shown as rounded, and the upper part of the reach-socket curved to correspond therewith. This construction is not essential, although I find that it gives additional stability. It is of course necessary that the two parts of the socket shall be locked firmly together, so as to prevent the slightest movement in use, and, furthermore, that the strain upon the two parts of the socket shall be equalized, so that the socket shall be just as strong as it could possibly be if made in a single piece. With this end in view I provide the lower part with a shoulder 9, which is engaged by a corresponding shoulder on the upper part. The drawing strain in use is of course upon the front axle, and is transmitted by the reach to the rear axle. The clip passes through both parts of the reach-socket and binds them closely together. The shoulder upon the lower part engaged by a corresponding shoulder on the upper part therefore insures that the drawing strain be equalized in the entire socket; in other words, that there be no undue strain upon the upper part alone, and that its full share of strain in use be taken up by the lower part of the socket. In order to avoid the additional weight, as well as the expense of surplus metal, the metal of the lower part is bent upward, as at 10, in the dies. This avoids any great amount of end-wise displacement of metal in the dies, and enables me to form both parts from small-sized strips or rods. In order to give additional strength and to prevent the possibility of lateral movement of the parts of the socket in use, I have in Figs. 1, 2, and 3 shown one of the parts—the upper, in this instance—as provided with a rib or spline 7, which engages a corresponding groove 8 in the other part, thereby locking the parts in place after they are assembled. It will thus be seen that by forming the two parts of the socket substantially as shown in Fig. 1 I secure ample strength to stand any strain that can possibly be brought to bear in use, avoid surplus metal, and, what is of equal importance in the better

grades of wagons, give to the parts a neat and finished appearance.

11 denotes the reach, which is fastened between the two parts of the socket by the usual bolts 12. The upper ends of these bolts are preferably squared, and passed through squared holes 13 in the upper part, and through round holes 14 in the lower part, as clearly shown in Fig. 2. Reaches are of course ordinarily made double. I have not, however, deemed it necessary to show both parts of a reach in plan, as the construction is in common use.

Having thus described my invention, I claim—

1. A reach-socket made in two parts, both of which in use extend past the axle on both sides and are provided with corresponding holes to receive the clip, the upper part having on its under side a transverse shoulder, which is engaged by a corresponding shoulder on the upper side of the under part, whereby the strain upon the parts is equalized.

2. A reach-socket made in two parts, one of said parts having a longitudinal groove, and the other a longitudinal rib engaging therewith, and the lower part having a transverse shoulder, which is engaged by a corresponding shoulder on the upper part, as and for the purpose set forth.

3. The combination, with the reach and axle of a wagon, of a reach-socket made in two parts, the lower part having a transverse shoulder engaged by a corresponding shoulder on the upper part, and a clip encircling the axle and passing through both parts, substantially as described and shown.

In testimony whereof I affix my signature in presence of two witnesses.

FRANK. E. WILCOX.
